CLAIM

The ornamental design for a device for supplying oxygen or other gases to water, as shown and described.

DESCRIPTION

FIG. 1 is a top perspective view of a device for supplying oxygen or other gases to water showing our new design; FIG. 2 is a side view of the embodiment of FIG. 1; FIG. 3 is another side view of the embodiment of FIG. 1; FIG. 4 is another side view of the embodiment of FIG. 1 opposite to the view of FIG. 2; FIG. 5 is another side view of the embodiment of FIG. 1 opposite to the view of FIG. 3; FIG. 6 is a top plan view of the embodiment of FIG. 1; FIG. 7 is a bottom plan view of the embodiment of FIG. 1; FIG. 8 is a top perspective view of another embodiment of the present design; FIG. 9 is a side view of the embodiment of FIG. 8; FIG. 10 is another side view of the embodiment of FIG. 8; FIG. 11 is another side view of the embodiment of FIG. 8 opposite to the view of FIG. 9; FIG. 12 is another side view of the embodiment of FIG. 8 opposite to the view of FIG. 10; FIG. 13 is a top plan view of the embodiment of FIG. 8; and, FIG. 14 is a bottom plan view of the embodiment of FIG. 8.
